US00D994318S

(12) **United States Design Patent** (10) **Patent No.:** **US D994,318 S**
(45) **Date of Patent:** **** Aug. 8, 2023**

(54) **PILL HOLDER**

(71) Applicant: **Apothecary Products, LLC**,
Burnsville, MN (US)

(72) Inventors: **Daniel Darst**, Zimmerman, MN (US);
Jennifer Joy Kallemyen, Savage, MN
(US)

(73) Assignee: **Apothecary Products, LLC**,
Burnsville, MN (US)

(**) Term: **15 Years**

(21) Appl. No.: **29/774,003**

(22) Filed: **Mar. 12, 2021**

(51) LOC (14) Cl. **03-01**

(52) U.S. Cl.

USPC **D3/203.3**

CLAIM

The ornamental design for a pill holder, as shown and described.

DESCRIPTION

FIG. 1 is a top perspective view of a pill holder, according to our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a bottom perspective view thereof.

The broken lines depict portions of the pill holder that form no part of the claimed design.

1 Claim, 7 Drawing Sheets
